COMBINED FLOWERPOT AND STAND THEREFOR

Romigio Dottavio, Pittsfield, Mass.

Application October 4, 1948, Serial No. 148,960

Term of patent 3½ years

(Cl. D35—3)

To all whom it may concern:

Be it known that I, Romigio Dottavio, a citizen of the United States, residing at Pittsfield, in the county of Berkshire and State of Massachusetts, have invented a new, original and ornamental Design for a Combined Flowerpot and Stand Therefor, of which the following is a specification, reference being had to the accompanying drawing, forming part thereof.

Fig. 1 is a front perspective view of a combined flowerpot and stand therefor showing my new design; and

Fig. 2 is a side perspective view thereof.

I claim:

The ornamental design for a combined flowerpot and stand therefor, as shown.

ROMIGIO DOTTAVIO.
